UNITED STATES PATENT OFFICE.

WILLIAM HENRY MASON, OF LEESBURG, OHIO.

FENCE-GRIPPING DEVICE.

1,393,807.

Specification of Letters Patent. Patented Oct. 18, 1921.

Application filed November 19, 1919. Serial No. 339,061.

To all whom it may concern:

Be it known that I, WILLIAM HENRY MASON, a citizen of the United States, residing at Leesburg, in the county of Highland and State of Ohio, have invented certain new and useful Improvements in Fence-Gripping Devices, of which the following is a specification.

The object of this invention is to provide 10 a simple, economical and effective device for use in stretching or erecting woven wire fence.

The invention is embodied in the example herein shown and described, the features of 15 novelty being finally claimed.

In the accompanying drawing—

Figure 1 is a plan view of a fraction of the device.

Fig. 2 is a sectional view on the line II—II 20 Fig. 1, looking up.

Fig. 3 is a sectional detail of the cam clamping member.

Fig. 4 is a perspective illustrating the manner of using the device.

25 In the views 5 and 5^a designate two bars of equal length longitudinally bent to form a tongue on one and a groove on the other so that when they are placed to embrace the fence at its opposite sides and clamped 30 together they grip the fence with a tight non-slipping engagement. The bar 5, which contains the longitudinal groove, has fixed to it at several points keepers 6 having inwardly turned lugs or hooks 6^a, while the 35 bar 5^a has journaled to it upon pins 12 at similar points circular members 7. Each of the circular members has at or near its rim two arcuate cam portions 7^a that work under the lugs 6^a so that when the circular member 40 is turned in the proper direction the bar 5^a is pressed toward the bar 5 to effect the clamping of the wire fence between them. The center of each of the circular

members is provided with a square boss 8 to receive a socket wrench for turning the 45 member.

Two of the keepers 6 are shown as provided with an eye 9 adapted to receive the end of a drawing chain 10 the latter designed to be operated by a suitable winch 50 or other tightening means.

In practice an end of the fence is first secured to a stout post and then the device of my invention applied to the fence farther along and while lying on the ground. The 55 device with the fence is then turned to erect position as shown in Fig. 4 and the fence stretched by drawing upon the chains 10. As soon as properly stretched the fence is secured to a succeeding post, all in the manner usual in erecting woven wire fence.

The forms of the parts can be changed without departing from the gist of the invention as claimed.

What I claim is:

1. A fence stretching device including, in combination, a pair of gripper bars, one of which is provided with transverse keepers having lugs turned inward toward each other to lie over the longitudinal margins 70 of the bar, cam members pivoted on the other bar, said cam members each having opposingly arranged portions to work under said lugs opposite the margins of the bars to squeeze the bars together. 75

2. A fence stretching device including, in combination, a pair of gripper bars, one of which is provided with keepers, each including lugs turned inward toward each other, circular members pivoted to the other bar, said circular members each having opposingly arranged cam members near its rim to work under said lugs and means whereby said circular members may be turned. 80

WILLIAM HENRY MASON.
